CLAIM

The ornamental design for a retractable leash headlight and flasher, as shown and described.

DESCRIPTION

FIG. 1 is a top plan view;

FIG. 2 is a rear elevational view;

FIG. 3 is a right (outer) side elevational view;

FIG. 4 is a front elevational view;

FIG. 5 is a bottom plan view;

FIG. 6 is a left (inner) side elevational view;

FIG. 7 is a perspective view of a retractable leash headlight and flasher shown attached to a retractable leash. The retractable leash shown in broken lines is for illustrative purposes only and does not form a part of the claimed design; and,

FIG. 8 is another side view of a retractable leash headlight and flasher, shown in reduced scale, depicting a typical application. The retractable leash, dog, and notional light beams shown in broken lines are for illustrative purposes only and do not form a part of the claimed design.
